UNITED STATES PATENT OFFICE.

JONAS WILFRID DRAKE, OF HALIFAX, ENGLAND.

APPARATUS FOR CONTROLLING THE DRAFT ON FURNACES.

1,414,631.

Specification of Letters Patent.

Patented May 2, 1922.

Application filed March 10, 1917. Serial No. 154,063.

To all whom it may concern:

Be it known that I, JONAS WILFRID DRAKE, a subject of the King of Great Britain, and resident of Halifax, in the county of York, 5 England, have invented a certain new and useful Improvement in Apparatus for Controlling the Draft on Furnaces, of which the following description, having reference to the accompanying sheets of drawings, is 10 a specification.

In connection with many and varied furnaces, but especially in connection with the regenerative furnaces used in the manufacture of gas (where the draft thereon is introduced by a chimney or uptake) the draft on the furnace and therefore the amount of air for supporting combustion therein is varied according to atmospheric conditions, either as to the temperature of the atmosphere or 15 the direction of the wind or both, with the result that at one time the heat of the furnace or consumption of fuel therein may be 20 as desired, yet at another time the draft thereon may be so strong as to increase the heat thereof and consequently the consumption 25 of fuel therein far beyond the desired extent for the purpose for which the furnace is used.

To obviate these undesirable results by 30 producing means whereby the draft on the furnace may be automatically regulated and kept constant thus preventing the disturbance of predetermined conditions in connection with the furnace, is the object of my 35 present invention, and my said invention relates to apparatus which I mount in the flue or in a part adjoining said flue between the furnace and the uptake of the chimney, so that the draft on said chimney, when it exceeds a given force, will act upon my apparatus causing same to admit air from the outside and not through the furnace, the volume admitted being such as to meet the demands of the extra draft and therefore 40 keep the draft on the furnace constant or approximately so. In apparatus constructed in accordance with my invention, the part acted upon and primarily moved by the chimney's draft does not itself uncover any 45 opening for the admission of air, but by being connected to other parts these latter are by its comparatively slight movement operated by it to open inlet spaces of considerable magnitude.

50 In carrying my invention into effect I

make use of the devices illustrated in the accompanying sheets of drawings wherein:

Fig. 1 is a sectional side elevation of my apparatus as mounted over a cavity or chamber adjoining the base of a chimney or uptake.

Fig. 2 is a sectional plan taken on the irregular line A—B of Fig. 1 when the parts have been moved by the chimney's draft.

Figs. 3 and 4 are views similar to Figs. 1 and 2 respectively but illustrate an alternative method of forming and mounting a certain part so that oscillatory motion may be transmitted thereto instead of said part having reciprocatory motion by being constructed and arranged as illustrated by Figs. 1 and 2.

Fig. 5 is a similar view to Fig. 1 but illustrates another form of the apparatus and method of mounting same so that oscillatory instead of reciprocatory motion may be made use of.

Fig. 6 is a sectional side elevation of a modified form of apparatus hereinafter described.

Fig. 7 is a view of the part shown by Fig. 6 as seen in the direction indicated by the arrow a.

Fig. 8 is sectional side elevation of a further modification hereinafter described.

Most of the parts of the apparatus are constructed of sheet metal which is comparatively thin therefore the parts of it which are illustrated as being cut through, are shown in lines of increased thickness instead of being shown by section lines.

To attain the object of my invention I mount an appropriate bell or other shaped device 2 which will cover or take over a sleeve 3 (or other structure as hereinafter described) in order that same may move vertically over said sleeve 3 with a minimum of space between the outer periphery of the latter and the inner surface of the former so that as little leakage of air as possible will take place through such space. The bell 2 is connected by a light connecting rod, cord or wire 5 to the arm of a lever 6 which is pivoted at 6^a upon a horizontal support 7. This support 7 is mounted upon the vertical bars 8 and 8^a. The other arm of the lever 6 has suspended from it by means of the connecting wire or cord 5^a another bell 9. This bell 9 takes over a sleeve or fixed bell 10 which is mounted within it and

which has its upper end covered by the end wall 10^a for the purposes hereinafter described.

Through the walls of the bell 9 slots 9^a (the lengths of which extend circumferentially) are formed and correspond in number and size approximately with slots 10^b formed through the walls of the inner bell 10. These slots in both cases are approximately of even width while the width of the metal, as 9^b and 10^a between these slots is rather larger in order that same is enabled to cover the openings or slots in each case. Thus when the outer bell 9 is in its normal position over the inner bell 10 (as illustrated by Fig. 1) the solid portion 9^b of the walls of the said bell 9 cover the openings 10^b of the inner bell 10 while the solid portions 10^a of the wall of the inner bell 10 will cover the slots or openings 9^a which are through the walls of the bell 9.

The bell 9 with its counterbalancing weight 16^a is arranged to be heavier than the bell 2 consequently when in its normal position the lower edge 2^a of the bell 2 will occupy a position above the case or stop piece 4 surrounding the sleeve 3 and this space between the lower edge of the bell 2 and the annular piece 4 approximately equals the spaces 9^a and 10^b through the walls of the bells 9 and 10.

As is illustrated the bells 2 and 9 and the parts in connection therewith are mounted above a cavity or space 11 which is enclosed at its base and all its surrounding walls except the opening 12, which leads therefrom into the chimney or uptake 13, and the opening 14 which leads through the upper wall of said cavity 11 into the bell 40 and sleeve 2 and 3 respectively. A further opening 15 is also made through the upper wall of the cavity 11 to lead into the inner bell 10. As is before stated the bell 9 is arranged to be slightly heavier than the bell 45 2 or this may be made adjustable by having counterbalancing weights 16 and 16^a mounted upon the lever 6 to attain the object desired. As is before stated the lever 6 is mounted upon its fulcrum which is of a 50 character that will reduce friction to a minimum in order that a comparatively small force acting upon the bell 2 is enabled to have the effect of causing same to descend to raise the bell 9 so that the slots made 55 through same will be brought opposite the slots made through the walls of the bell 10 within it.

As will be observed the apparatus is mounted so that the uptake of the chimney 60 13 has free access to the interior of the chamber 11, the sleeve 3 and bell 2 as well as to the bell 10 so that the draft on said uptake when exceeding a certain power causes the bell 2 to descend by acting directly thereon to somewhat exhaust or suck

away the air from within the chamber 11 and the sleeve and bell 3 and 2, whereas the same suction does not interfere with the air within the bell 9 since the cover 10^a of the bell 10 within it, is a protection 70 against such action.

From the foregoing description it will be seen that when the draft on the chimney exceeds a given power, it has the effect of causing the bell 2 to descend and simultaneously causes the bell 9 to rise in order that cool air from the atmosphere may then be permitted to pass through the openings in the two bells 9 and 10 down into the chamber 11 through said chamber and into 80 the uptake 13 somewhat as indicated by the arrows to counteract the draft in said uptake in order to bring it to its normal conditions on which the descending of the bell 9 will again bring the parts into their normal positions.

In the arrangement of the devices hereinbefore described the air inlets are opened and closed by the bell 9 moving lengthwise over the bell 10, however by mounting the 90 inner bell 10 upon a vertical shaft 10^d Fig. 3 (the lower end of which rests upon a foot step 10^e while the upper end is supported laterally by the bearing 10^f) said bell 10 may have oscillatory motion transmitted to 95 it. In this case the bell 9 is fixed and has the bearing 10^f mounted upon it, while through a lateral opening in said bearing, an arm 10^g may extend to be engaged with by a connecting rod 5^b. The arm 10^g is 100 fixed to the shaft 10^d and the rod 5^b engaging with it is coupled to a pendant arm 6^b of the lever 6, by which arrangement the movements of the bell 2 are transmitted to the bell 10 to cause it to oscillate in order 105 to bring its slots 10^b opposite the slots 9^a in the bell 9. In this arrangement of devices the slots in the bells 9 and 10 are made to extend lengthwise.

Instead of mounting the bells 9 and 10 110 with their axes in the vertical plane I may arrange them to have their axes in the horizontal plane and I may then modify their shape by having them of semi-cylindrical form as shown by Fig. 5 in which arrangement the semi-cylindrical drum 17 takes the place of the bell 9 while the drum 18 takes the place of the bell 10. The semi-cylindrical drum 17 is pivoted at each of its extremities 17^b upon bearings 17^c which will produce little friction against its oscillations. The drum 17 has longitudinal slots 17^a formed through its walls corresponding with slots 18^a formed through the inner semi-cylindrical drum 18 and the weighting 125 of the drum 17 by the counterbalancing weight 16^a causes it to occupy a normal position as illustrated by Fig. 5 so that on the draft in the uptake acting upon the bell 2, it causes this bell 2 to descend thus bring- 130

ing with it the lever 6 to oscillate the outer drum 17 to which it is connected by the connecting rod 5^a so as to effect the counter-acting of the draft as hereinbefore explained.

By making use of curved or segmental drums (17, 18) one to rotate or oscillate over or within the other, I may make use of a simple valve 22 (see Figs. 6 and 7) to operate same by arranging said valve 22 to have pivotal points 22^a resting upon supports or footsteps 23 while arms 22^b extending longitudinally therefrom have the drum 18 fixed upon them. These arms and the drum 18 are counterbalanced by the weight 16^b which is adjusted so that when a supplementary counterbalancing weight 16^c is in its position nearest the pivots 22^a the normal position of the valve 22 will be where it rests 20 against the encircling flange 24 (which covers the outer edges of the valve 22 as shown by Fig. 6) by which arrangement we may then adjust it to move by the action of the draft of the chimney under any greater 25 weight that may be desired by moving said weight 16^c along its supporting bar 16^d.

In this arrangement of the devices the sleeve 3 is placed horizontally and leads to the chimney 13 without passing through the 30 cavity 11.

As a further modification I may arrange the inner drum 18 as illustrated by Fig. 8 so that it shall be fixed and have egress from it through the opening 19 in the upper walls 35 of the cavity 11. In this case the outer drum 17 which is pivoted at 17^b will have its wall 17^c brought under the action of the draft through the uptake 13 and cavity 11 which has access to said wall 17^c through the opening 20, thus when the draft exceeds the 40 desired strength said wall 17^c will be drawn in a downward direction sufficiently to cause the outer drum 17 to oscillate and bring the openings through its wall opposite to the 45 openings through the drum 18 to permit air to enter the cavity within in order that same may pass through the chamber 11 to the uptake as will be understood.

In the varied forms of the hereinbefore 50 described apparatus I have illustrated the bell 2 as having great influence over the parts which control the openings for the ingress of cool air or in other words I have shown the apparatus so constructed and arranged that by a slight movement on the 55 part of the moving body actuated by the draft of the chimney considerable space is afforded for the ingress of air and that to a greater extent than may sometimes be required, hence under certain conditions it

may be possible to make use of bells such as 9 and 10 without slots or openings but with sufficient freedom at their bases as to enable the movement of the one over the surface of the other to lay bare such space or opening 65 for the ingress of air as will answer the purposes desired.

The bells 2, the wall 17^c and the valve 22 are the parts primarily moved by the chimney's draft and in no case do they by such 70 movement uncover any passage in which they are situated, to permit the ingress of air. And since the functions of the bells 2, the walls 17^c, and the valve 22 are in all 75 cases identical, the word "valve" used in the claiming clauses has reference to one or other of said devices.

In the accompanying illustrations the bells or apparatus are shown as mounted over a cavity 11 which is an off-shoot from 80 the chimney or uptake 13 but I am aware that my apparatus may be placed in any horizontal flue or other appropriate position where it can operate between the furnace and the chimney or uptake. 85

Such being the nature and object of my said invention what I claim is:—

1. In an apparatus for the purpose described, the combination of a chimney having two openings to the outer air formed 90 therein, a valve supported to close one of said openings, means controlling the admission of air to the other opening comprising a stationary slotted member and a movable slotted member, and means connecting 95 the last member and said valve.

2. In an apparatus for the purpose described, the combination of a chimney having two openings to the outer air formed 100 therein, a valve supported to close one of said openings, means controlling the admission of air to the other opening comprising a stationary slotted member and a movable slotted member, and arms extending 105 from the valve and supporting said movable slotted member.

3. In an apparatus for the purpose described, the combination of a chimney having two openings to the outer air formed 110 therein, a valve supported to close one of said openings, means controlling the admission of air to the other opening comprising a stationary slotted member and a movable slotted member, a lever fulcrumed between the valve and movable slotted member 115 to rock about a horizontal axis, connections between one arm of said lever and the valve, and means connecting the other arm of the lever to said movable slotted member.

J. WILFRID DRAKE.
